[57] CLAIM

The ornamental design for a power tap outlet strip, as shown.

DESCRIPTION

FIG. 1 is a perspective view from the top, left side of the article embodying the invention;

FIG. 2 is a front elevational view of the article embodying the invention;

FIG. 3 is a top plan view of the article embodying the invention;

FIG. 4 is a left side elevational view of the article embodying the invention;

FIG. 5 is a rear elevational view of the article embodying the invention;

FIG. 6 is a right side elevational view of the article embodying the invention; and,

FIG. 7 is a bottom plan view of the article embodying the invention.

The broken line showing throughout the drawing figures is included for the purpose of illustrating environmental structure only and forms no part of the claimed design.
